UNITED STATES PATENT OFFICE.

JOSEPH E. MCKEE, OF CONNELLSVILLE, PENNSYLVANIA, ASSIGNOR OF ONE-THIRD TO
N. E. WOOLMAN AND ONE-THIRD TO JOSEPH OPPMAN, BOTH OF CONNELLSVILLE,
PENNSYLVANIA.

BATTERY CONNECTER.

Application filed March 30, 1921. Serial No. 457,090.

To all whom it may concern:

Be it known that I, JOSEPH E. MCKEE, a citizen of the United States, residing at Connellsville, in the county of Fayette and State of Pennsylvania, have invented certain new and useful Improvements in Battery Connecters, of which the following is a specification.

This invention relates to improvements in connectors adapted for use in attaching and detaching electrical conductors to and from the binding posts or other similar contacts of electrical batteries, instruments, and the like.

The principal object of the invention is to provide for a device of the character mentioned, and one adapted to be permanently, or otherwise securely attached to the free end of a conductor and of a nature to admit of its quick attachment to or detachment from the binding posts of electrical devices as aforesaid.

A further object of the invention is to provide for a connector of the class described, and one which, in addition to its adaptability for quick attaching and detaching action, effects a firm and secure gripping action on the engaged binding posts or contacts in a manner to assure of highly efficient electrical contact with the latter.

With the foregoing and other objects in view, the invention resides in the certain novel and useful construction and arrangement as will be hereinafter more fully described, set forth in the appended claims, and illustrated in the accompanying drawing, in which:

Figure 1 is a side elevation of the device in its inoperative position.

Fig. 2 is a view similar to that of Fig. 1 but showing the device in its operative position.

Fig. 3 is an end elevation thereof, and, Fig. 4 is a bottom plan view of the device as in Fig. 1.

Referring to the drawing, wherein similar characters of reference designate corresponding parts in the several views thereof, the body portion of the connector is formed of a suitable length of spring metal bent into a substantially yoke or inverted U-shaped configuration, whereby to provide oppositely disposed leg portions 10 projecting from the head or body 11 thereof disposed on reversely curved lines to provide a

medially depressed portion 12 forming a seat and into which is laid the bare end 13 of a conductor 14. The end 13 is suitably secured permanently in position as by being brazed or soldered thereto. The free ends 60 of the leg portions 10 are each bent inwardly to provide angularly disposed portions or gripping jaws 15, the free end edges thereof being opposed one to the other and toothed or serrated, as at 16, whereby to facilitate 65 the gripping action thereof.

Medially of the opposite leg portions 10 is formed vertically elongated openings or slots 17 one in alignment with the other, and passed through these openings or slots 70 17 is a latch bar 19 which has a recess 20 formed in the under edge of an enlarged end portion 19' thereof adapted to engage the lower wall or edge of one of the openings, and a series of inwardly inclined rack 75 teeth 21 extending inward from the opposite end of the lower edge thereof which are adapted for cooperation with the lower wall or edge of the slot or recess of the other of said openings, whereby to retain the leg portions 10 in any desired position one with respect to the other throughout the range of adjustment necessary for the proper manipulation and use of the connector.

In the use of the device, after a conductor 85 14 has been attached as hereinbefore indicated, the leg portions 10 are pressed toward each other until the serrated jaws 15 are firmly engaged at opposite sides of a binding post or the like (not shown), and 90 preferably under the usual binding nut thereof, whereby to make good electrical contact therewith. In pressing the leg portions 10 toward each other, the inward inclination of the rack teeth 21 admits of the 95 free movement of the leg portion complementary thereto, the teeth 21 riding over the edge of the slot cooperating therewith for such purpose. However, when the leg portions 10 have been brought into the desired 100 clamping position on a binding post or other electrical contact, their accidental spreading from such adjusted position is prevented by the vertical faces of the teeth 21 being abutted by the outer wall of the complementary 105 leg portion. To release the connector from operative position, the latch bar 19 is swung upwardly on the fulcrum point of the same, as provided by the recess 20 thereof being engaged over the lower edge of the opening 110

in the other leg portion opposite to the one complementary to the rack toothed end of the latch bar 19, and the leg portions will swing apart. It is to be here noted that the natural resiliency of the leg portions 10 is fixed, or otherwise determined in the manufacture of the connector, and is arranged to permit the spread of the same at a distance apart slightly less than the length of the latch bar 19, so that the latter is not free from engagement with the slots or recesses thereof except when desired. The enlarged end portion 19' is of a width to snugly engage in the slot or recess complementary thereto, and to facilitate its insertion into operative position in the latter the outer portion of its top edge is curved, as at 20', so that to have its recess 20 engaged over the lower edge of this particular slot or recess 17, the latch bar must be held in a downwardly inclined position during the movement of insertion, and, consequently, by reason of this peculiar construction, arrangement and necessary manipulation, the latch bar 19 will always remain in its operative position during the continued use of the device, and can only be removed entirely from between the leg portions 10 by spreading the latter sufficiently to free the rack toothed end thereof from the opening complementary thereto, and canting the bar in a downward direction until a sufficient clearance has been effected for the passage of the curved portion of the top edge of the same inward of the upper portion of the engaged slot or recess.

Having thus fully described the invention, what is claimed, is:—

1. A connector for the purpose set forth comprising a yoke shaped body of resilient material having the head thereof provided with a seat to which is adapted to be permanently secured a conductor, said member having the legs thereof provided with inwardly extending jaws, each of the legs of

said member provided with a slot, and a latch bar extending through said slots and notched near one end for removable engagement with the inner end wall of a slot of one of the legs, said latch bar further provided with a series of teeth capable of engaging the inner end wall of the other of said slots for securing said jaws in operative position.

2. A connector for the purpose set forth comprising a yoke shaped member of resilient material adapted to have a conductor permanently secured therewith, said member having the free ends of the legs thereof provided with inwardly extending jaws adapted to be brought into abutting engagement, each of the legs of said member formed with a slot, and a latch bar extending through said slots and notched to removably engage one of the walls of the slot and further provided with a series of teeth capable of engaging a wall of the other of the slots for securing said jaws in abutting engagement.

3. A connector for the purpose set forth comprising a yoke shaped member of resilient material adapted to have a conductor permanently secured therewith, said member having free ends of the legs thereof provided with inwardly extending jaws adapted to be brought into abutting engagement, each of the legs of said member formed with a slot, and a latch bar extending through said slots and notched to removably engage one of the walls of the slot and further provided with a series of teeth capable of engaging a wall of the other of the slots for securing said jaws in abutting engagement, the notched end of said bar being of greater width than the toothed end thereof.

In testimony whereof, I affix my signature hereto.

JOSEPH E. MCKEE.
